UNITED STATES PATENT OFFICE.

EDWARD W. EDWARDS, OF CINCINNATI, OHIO.

STOVEPIPE.

1,153,204.

Specification of Letters Patent. Patented Sept. 14, 1915.

Application filed June 28, 1915. Serial No. 36,797.

To all whom it may concern:

Be it known that I, EDWARD W. EDWARDS, a citizen of the United States of America, and a resident of Cincinnati, county of Hamilton, State of Ohio, have invented certain new and useful Improvements in Stovepipes, of which the following is a full and clear specification, reference being had to the accompanying drawings, in which—

- 10 Figure 1 is a perspective view of a section of the stove pipe with its edges connected ready for use; Fig. 2 a fragmentary perspective view, enlarged, showing the joint connected; Fig. 3 a similar view showing the parts approximately as they appear during the act of connecting up the joint; and Fig. 4 a view similar to Fig. 2 showing a slightly different form of tongue.
- 15

The object of this invention is to provide 20 the longitudinal meeting edges of the section with means whereby the seam at that point may be interlocked at the place of sale or use of the section, thereby permitting the sections to be transported and shipped with 25 their longitudinal seams open the full length of the sections, and so that the sections may be conveniently nested, as more fully herein-after set forth.

On one of the longitudinal edges *a* of the 30 section is formed a flange *b*, this flange being bent into shape from an extension of the edge of the sheet and being arranged to extend along the interior of the pipe. This flange is shaped so as to form two channels 35 *c*, *c'*, the former lying under and back of the edge *a* of the sheet and the latter lying a short distance away from the edge of the sheet, the space between the edge of the sheet and the free edge *d* of the outer wall of the 40 channel *c'* forming a throat or entrance to the channels.

The other edge *a'* of the sheet is provided 45 with a tongue *e* extending the full length of the sheet and offset inwardly from the same sufficiently to be inserted in the channel *c*, this offset of the tongue forming a longitudinal shoulder *f* and serving to maintain the circumferential alinement of the parts *a* and *a'* of the pipe section. When the parts are 50 interlocked, the edge portion *a'* of the pipe section rests against the front face of the front wall of the channel *c'*, so that said channel *c'* lies under said edge portion *a'* just as does the channel *c* under the opposite 55 edge *a* of the sheet. To hold the tongue *e* in the channel *c* and thus interlock the edges

of the section together, the part forming the shoulder *f* is inclined slightly backwardly so that the free edge *d* of the channel *c'* will interlock with the shoulder, said free edge 60 bearing against the shoulder its full length at the junction of the shoulder with the edge *a'* of the sheet. The inner edge of the shoulder will bear against the flange *b* at a point opposite the throat, and the free edge of the 65 tongue *e* will bear outwardly against the inner wall of the channel *c*, thus forming a smoke and gas-tight joint extending the full length of the pipe section.

To connect and interlock the edges of the 70 sheet, the tongue *e* is inserted into the throat of the two channels and then the two edges of the sheet are pressed inwardly, as shown in Fig. 3, far enough to cause the shoulder *f* to spring past the free edge *d*, whereupon 75 said free edge will engage behind the oblique shoulder and thus interlock the parts, making a strong, smooth and neat joint extending the full length of the pipe section. A feature of special importance is that the 80 backward bending of the shoulder *f* and its engagement with the free edge of the channel *c'* provides a solid abutment extending the full length of the pipe section, this abutment serving to resist the expansive tendency 85 of the pipe when highly heated. To render the joint still further proof against leakage of gas or smoke, the tongue *e* may be bent or crimped longitudinally, as shown at *e'* in Fig. 4, so that said bent part will 90 bear against the front wall of the channel *c* and the extreme free edge of the tongue will bear against the inner wall of the channel *c*, thus providing three contacting points 95 throughout the length of the joint.

Having thus described my invention, what I claim is:

1. A sheet metal stove pipe section having formed along one edge of the sheet a flange bent to form two channels facing each other, 100 these channels lying in the interior of the pipe and having a narrow entrance or throat along the edge of the sheet, and the other edge of the sheet being formed into a longitudinal tongue, said tongue being formed 105 with an inwardly and backwardly extending shoulder adapted to enter one of the channels and with a free edge adapted to enter the opposite channel.

2. A sheet metal stove pipe section having 110 formed along one edge of the sheet a flange bent to form two channels facing each other,

these channels lying in the interior of the pipe and having a narrow entrance or throat along the edge of the sheet, and the other edge of the sheet being formed into a longitudinal tongue, said tongue being formed with an inwardly and backwardly extending shoulder adapted to enter one of the channels and with a free edge adapted to enter

the opposite channel, said free edge of the tongue being bent or crimped longitudinally throughout its length, for the purpose set forth.

In testimony whereof I hereunto affix my signature.

EDWARD W. EDWARDS.
